G. A. BURNHAM

OIL FILLED INSULATING BUSHING

Filed July 23, 1926

UNITED STATES PATENT OFFICE.

GEORGE A. BURNHAM, OF SAUGUS, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS.

OIL-FILLED INSULATING BUSHING.

Application filed July 23, 1926. Serial No. 124,535.

This invention relates to high tension oil or compound filled insulating bushings of the type having an oil reservoir at the top.

A high tension bushing usually has one or 5 more joints that must be maintained oil tight in order to maintain the insulating property of the insulator; and it is of advantage to keep down the number of joints through which oil may escape.

10 It is an object of this invention to provide an improved construction for an oil filled bushing of the above type in which the necessity for an oil seal at the top of the outer porcelain tube is obviated; and more specifically 15 to provide a bushing of this type having means to indicate the level of the oil in the bushing, which oil level is arranged to be below the top of the outer porcelain shell.

It is a further object of the invention to 20 provide an indicating device for an insulating bushing which will give visible evidence of the operating temperature of the interior of the bushing.

25 A further object is generally to improve the construction and performance of oil filled bushing type insulators.

Fig. 1 is an elevation, partly in section, of 30 the insulating bushing embodying the invention.

Fig. 2 is a sectional elevation of the top of the insulator of Fig. 1 showing the oil reservoir and indicating device.

Fig. 3 is a section on the line 3—3 of Fig. 2.

Fig. 4 is a section on line 4—4 of Fig. 2.

35 As here shown, the insulator embodying the invention includes an outer porcelain casing, or shell, of substantial length which comprises an upper section 10, a middle section 12, and a lower section 14. Said upper

40 section 10, and said middle section 12 of the outer casing have straight cylindrical side walls 16 which are provided externally with a series of uniformly spaced capes, or petticoats 18, as is customary with insulators for outdoor use.

45 Said lower shell section 14 has tapered cylindrical side walls 20 which contract at the bottom to a relatively small axial passage in the bottom of the casing. Said walls 20 are provided with external surface corrugations 22 in the usual manner to reduce surface leakage at that end of the insulator.

Said outer casing is adapted to contain a

body of insulating oil or other electrically-insulating fluid and consequently means with 55 which this invention is not specifically concerned has been provided to render the joints between the several sections thereof fluid-tight.

A conducting stud 26 is disposed in the 60 axial passage through said shell and is fixed at its lower end to said lower shell section 14 in any suitable manner. Said stud is provided with a lower extended screw-threaded portion 28 to provide a terminal for said insulator, and a nut 29 is received thereon adapted to hold a yielding packing washer 30 against the lower end of said outer shell and provide a fluid-tight seal at the bottom 70 of the insulator. No difficulty is encountered in making this joint tight because of the relatively small area of the passage at the lower end of the insulator.

In accordance with this invention a metal bushing 32 having an outstanding annular 75 flange 34 is disposed within the open upper end of said shell section 10 and is spaced annularly therefrom and is secured thereto by a body of cement 36 which is disposed between said bushing and shell. Said bushing has an upstanding annular flange 38 which is internally screw-threaded to receive a thin metal cylinder 40 having slots or windows 41 at intervals about its circumference. A glass cylinder 44 is received on a yielding 80 washer 42 carried by said bushing and surrounds said cylinder 40 and is spaced therefrom by the upstanding flange 38.

A cap 46 forms the closure for the open top of said cylinders 40 and 44. Said cap is provided with an annular depending flange 48 which is internally screw-threaded removably to engage the upper end of said metal cylinder 40. A yielding packing is disposed in the annular groove formed by the outer depending rim 50 of said cap and said flange 48 to receive the upper edge of said glass cylinder 44 and provide a weather-proof joint at the top of said cylinder. Said cap 46 is further provided with an upstanding neck 52 having an 90 axial passage 53 therethrough in which the conducting stud 26 is received; and said stud has a screw-threaded portion 54 extending above said neck. Said stud is fixed to the insulator at the bottom thereof and is free for 95 axial movement in the passage 53 of said cap, 100 105

whereby to prevent injury to the porcelain shell due to expansion of the stud.

A terminal cap 56 is screw-threaded on said stud 26 at its upper end and said cap has a reduced screw-threaded end portion 58 which forms a terminal stud for the insulator. Said terminal cap is also provided with an annular apron 60 which depends in spaced relation about said neck 50 and forms a weatherproof covering for the passage 53 through said neck 52. The cap and stud may be pinned removably in the aforesaid relation by a pin 64.

A number of concentric tubes 65 of insulating material are provided within the outer casing and about the conductor which tubes are adapted to be spaced apart by suitable means to divide the space between the stud 26 and the outer shell into a number of annular intercommunicating oil-containing compartments. The insulating fluid is arranged to fill said outer shell and occupy the spaces, or compartments, between said inner insulating tubes 65. The supply of oil in the bushing 25 must not be allowed to diminish since a large part of its insulating properties would be lost; hence it has been customary to maintain the level of the oil at a point well above the top of the outer shell in a transparent cylinder 30 so that the level of the oil would be visible. This arrangement necessitated a fluid-tight joint at the top of the outer shell.

According to my invention, I provide a construction making it unnecessary to have a fluid-tight seal at the top of the insulator. In carrying out this provision, the oil level in the insulator is maintained at a point below the top of said outer shell and below the top of the cement connection between the flange 34 and the insulator. Since the connection thus is not under oil pressure, no especial means need be provided to maintain the connection oil tight, as has been the case heretofore. Since the oil level is below the top of the insulator, means is provided to indicate externally the condition of the oil level in the insulator.

Said means includes a hollow metal toroidal float-member 70 which is disposed loosely about the conductor within the insulator and is adapted to float in the oil therein and rise and fall in accordance with variations of oil level, being guided in such movements by the conductor. Said float member is fixed to the lower end of a tube 72 which is loosely disposed to slide freely on the conductor; and the upper end of said tube is terminated, with normal oil level, intermediately within the ends of the shell 40. A thin disc 74 is fixed to the upper end of said tube and is freely movable in said shell and comprises an indicator to make known, by inspection through the glass shell 44 and the apertures 41, the relative positions of the float and consequently the level of oil in the insulator. The appear-

ance of the disc within the middle portion of the glass shell may indicate the normal level of oil in the insulator.

The oil level within the insulator is adapted to rise and fall in accordance with temperature variations of the insulator and the float and disc may serve also as a temperature indicator for the insulator. The glass shell may be provided with indication-marks 76 which may cooperate with the disc 74 to make known the combined temperature and oil-level conditions within the insulator. The highest mark may indicate a dangerously heated condition of the insulator, at or above which the insulator may break down.

The insulator is provided with an annular supporting sleeve 82 intermediate its ends by which the insulator may be secured to the casing 84 of an electrical apparatus, or other support.

A thin sheet metal cup 78 is disposed within the upper end of the insulator and is secured in place by an outstanding flange 80 thereof, which flange is clamped between the sleeve 82 and the shell 40. Said cup is extended substantially beneath said float and is adapted to hold it from undue movement on the conductor when the insulator is dry or has insufficient oil therein, although the cup is not intended to limit the free movement of the float within its intended range of movement.

I claim:

1. An insulating bushing having the combination of an oil-containing insulating shell, a conductor disposed in the oil in said shell, and an oil-level indicator including a float-member disposed within said shell in the oil thereof and having a sliding connection with said conductor.

2. An insulating bushing having an outer open top porcelain casing adapted to contain oil to some level beneath the open top thereof, a stud disposed within said casing, an oil indicating means slidable on said stud and including a tube surrounding and slidable on said stud, a float secured to the lower end of said tube, and a pointer carried by the upper end of said tube, the upper end of said tube and said pointer arranged normally to extend above the open top of said casing.

3. An insulating bushing having a cylindrical outer shell including an opaque insulating tube and a separate upper transparent tube connected with said insulating tube, a body of oil disposed within said shell and below the top of said insulating tube, and fluid-governed means within said transparent tube arranged to indicate the level of the oil in said shell.

4. An oil filled bushing having an outer porcelain tube, a transparent chamber on the top of said tube, a body of oil disposed within said porcelain tube and below the top thereof, and fluid-level indicating means in said chamber actuated by the oil in said tube.

5. An insulating bushing comprising an outer open top porcelain tube adapted to contain a body of oil to some level beneath the top thereof, a metal cylinder having cut-
away portions connected with and disposed on the open top of said porcelain tube, a glass cylinder concentric with said metal cylinder, an axial stud disposed within said porcelain tube, an annular float surrounding said stud and adapted to be buoyed up by the oil within said tube, and fluid-level indicating-means governed by said float arranged for vertical movement on said stud and having a component which is visible within said metal cylinder.

6. An oil filled insulating bushing comprising an outer open top insulating shell, a casing which has a transparent portion joined to the top of said shell, an axial stud disposed within said shell, a body of oil contained within said shell to a level which is below the joint between said shell and casing, and a float-member floating on the oil and having a pointer located within said transparent casing.

7. An insulator including an opaque outer insulating shell adapted to contain oil to some level beneath the top thereof, a conducting stud disposed within said shell, and an oil-level indicating device contained within said

shell, and including a tube slidably disposed on said stud, a float secured to the bottom of said tube and adapted to be buoyed up by said oil, and an indicator carried by the tube above the top of said shell.

35

8. In an electric insulator the combination of an insulating tube, a transparent cylinder disposed on the top of said tube, a conducting stud disposed within said tube and extended through said cylinder, a metal cup contained within said tube mainly below the open top thereof and having a fluid passage through its bottom, a body of oil contained within said tube entirely below the open top thereof and partly filling said cup, a float disposed freely within said cup, and an indicator secured to said float and projecting into said cylinder.

9. An oil-filled type insulating bushing having an open top, a closure for said top having an oil-pervious connection with said bushing, said bushing adapted to contain oil to a level below the top and said oil-pervious connection, and a float-member disposed on the oil within said bushing below the top thereof and having an externally-visible oil-level indicator.

In testimony whereof, I have signed my name to this specification.

GEORGE A. BURNHAM.
